ARTHUR R. HARVEY, OF MIDDLETOWN, OHIO.

DEVICE FOR DETERMINING MOISTURE PERCENTAGE IN A WEB AND ROLL CONSTRUCTION THEREFOR.

Application filed September 4, 1924. Serial No. 735,921.

This invention relates to a device for determining the percentage of moisture in a web and particularly a paper web and to the construction of a roll adapted for contact 5 with the web and carrying the operating means for an indicator to register said percentage.

An object of the invention resides in providing a construction of improved form 10 adapted for contact with a movable web and carrying means for operating an indicator responsive to the heat of the web so that the indicator will register the moisture percentage in said web.

Another object of the invention resides in providing a device for indicating the moisture percentage in a web having an indicator and operating means connected therewith and including a rotatable element adapted 20 for engagement with the web and rotatable in the movement thereof, said rotatable element carrying heat responsive means connected with said indicator and adapted to operate the indicator according to the temperature of the web for indicating said percentage.

A further object resides in providing a device of the character described wherein the operating means for the indicator includes a roll suitably mounted for rotation 30 in contact with a movable web comprising a plurality of assembled sections, predetermined sections of which are provided with heat responsive means connected with said indicator to operate the same to indicate the percentage of moisture in the web.

Still another object of the invention resides in providing an operating means for an indicator including a roll mounted for 40 rotation and contact with a movable web, which includes a plurality of axially arranged assembled sections to form said roll, predetermined sections of which form heating sections, while other predetermined sections form cold sections, each of said predetermined sections being equipped with heat responsive means connected with said indicator, and effective through the temperature of the heating means and the web for operating 45 said indicator, to register the moisture percentage in said web.

Another and particular feature of the invention resides in the particular roll construction including a shaft or shaft members 50 adapted to mount the roll structure for rota-

tion in suitable bearings, and supporting structure for contact with a movable web, the roll structure including a plurality of axially arranged cylindrical sections carried by said shaft or shaft member for forming a 60 roll structure having a substantial tensile strength for withstanding the heavy pressure transmitted thereto by the web, due to the relative contraction thereof as it passes from a drying machine, in the course of 65 manufacture of the paper.

The invention also includes other objects and improvements in the details of construction and arrangement of the parts which are more particularly described in the 70 following detailed description and claims, directed to preferred forms of the invention, it being understood, however, that various changes in these details of construction and arrangement of parts may be made as suggested by the forms illustrated, or in any other manner, within the scope of the invention as described and claimed.

The accompanying drawings, forming a 80 part of this application illustrate the invention, and in which:

Figure 1 is a diagrammatic elevational view of an improved roll construction forming the subject matter of this invention.

Figure 2 is a longitudinal sectional view, 85 through the central portion of the roll illustrated in Figure 1, and illustrating more particularly the heating sections and manner of assembling adjacent sections thereto.

Figure 3 is a vertical sectional view, 90 through the end portion of the roll and the bearing structure for mounting the same on a paper machine.

Figure 4 is a diagrammatic elevational view of a roll construction similar to that 95 shown in Figure 1, having a plurality of heating sections positioned adjacent the ends of the roll.

Figure 5 is a sectional view through one of the heating sections of the structure 100 shown in Figure 4.

Figure 6 is a sectional view, through the end portion of the roll shown in Figure 4, showing the manner of mounting the end structure on the supporting shaft therefor. 105

Figure 7 is a transverse sectional view through the heating section of the roll shown in Figure 4, taken on the line 7-7 of Figure 5.

Figure 8 is a diagrammatic view showing 110

the last two rolls of a dryer, and the position of the roll forming the subject matter of the present invention therewith.

- 1 indicates an improved roll construction 5 or rotatable element adapted to be mounted for rotation in contact with a movable web, and which comprises a hot or heating section 2, positioned in the central portion of the roll, cold sections 3 adjacent the end 10 portions of the roll, and intermediate sections 4 between the hot and cold sections and end sections 5 at the end of said roll all assembled in axial alignment for forming the assembled roll structure in a manner 15 which will be presently described. The roll comprises a plurality of tubular casings forming the exterior cylindrical surface of the roll, which are co-extensive with each section and are indicated at 6, said casings 20 being threaded internally at opposite ends for threaded cooperation with junction members 7 having annular flanges 8, against which the ends of the tubular casings abut. The junction blocks or members 7 comprise 25 cylindrical portions 9 having threaded external surfaces for cooperation with the internal threads on said tubular casing, and web portions 10 in the central portion of said cylindrical portions 9 for reinforcing 30 said cylindrical portions, so that the blocks will cooperate with said tubular casings to form a roll structure having a substantial tensile strength. The webs 10 are provided with openings 11 for convenience 35 in passing connection wires to the heat responsive means therethrough.
- The heating section 2 and the junction blocks contiguous thereto are of special construction having axially arranged openings 40 12 for receiving a rod member 13 extending through said heating section and supporting a pair of spaced spiders 14 having annular flanges 15 thereon, arranged in opposed relation for receiving and mounting a cylindrical body 16, of suitable heat resisting material provided with a spiral groove on the periphery thereof for receiving an electrical heating element 17 adapted to be wound therein and connected with a suitable source 45 of electric current for supplying heat to said section, for heating the casing 6, in order to supply a predetermined amount of heat to the web passing over and in contact with said roll. The spiders 14 are held in spaced 50 relation by a plurality of tubes 18, arranged in circumferential relation. These tubes are adapted to form conduits for the circuit wires to the heating element 17, and also the hot junction of the thermocouple which 55 will be presently described. Suitable insulated current carrying wires 19 are connected with said heating elements 17 and extend through the tubes 18 and the openings 11 of the junction members of said roll to 60 contact rings on the end portion thereof.

A hot junction of a thermocouple is mounted in the casing 6, as indicated at 20, and includes a suitable block member containing the usual and well known thermocouple construction and from which leads a circuit wire 21 suitably insulated for connecting said thermocouple with a suitable contact ring at the end of the roll, to be presently described. The tube 18 adjacent the thermocouple 20 is provided with an opening 22 adapted to permit the cable 21 to pass therethrough so that it will properly support the cable or circuit wire throughout the heating section to prevent the same from becoming unduly heated or contacting with the circuit wires of the heating element.

The cold section 3 of the roll mounts the cold junction 3' of the thermocouple in the same manner as the hot junction illustrated in Figure 2, and from which the circuit wires extend for properly connecting this thermocouple in circuit with an indicator. The cold section merely includes the casing section 6 assembled in the roll structure by the junction members before described, and positioned between the tubular casing 6 of the intermediate sections 4 and the end section 5.

The end section 5 which is located at each end of the roll, includes an identical structure for each end, and is particularly illustrated in Figure 3 of the drawings. The end section comprises the usual tubular casing 6 common to all of the sections, secured to its adjacent section through the medium of the usual junction member above described, and mounting in the free end portion thereof at the end of the roll, an annular member of angular section indicated at 23, which is designed to make a tight fit within the casing 6 and to which is secured a face plate 24, fitted in the end of the casing 6 as illustrated in Figure 3 and secured to the annular member 23 by suitable bolts 25. This face plate is provided with a central opening surrounded by an annular flange which is threaded on or otherwise permanently secured to a shaft section 26, the end portion of which is adapted to be seated and carried by a suitable bearing structure 27 for rotatably mounting the roll in plate members 28 which are adapted to be secured to a suitable portion of the dryer frame for paper machines. The portion of the shaft extending through the flange parts of the face plate is provided with a plurality of grooves 29, which are adapted to provide passages for the circuit wires from the heating element and the thermocouple carried by the hot and cold sections of the roll. The shaft section 26 is of larger diameter at the inner end where it fits in the flange opening of the face plate, while the outer end portion received in the bearing 27

is of substantially reduced diameter, and between said end portions of varying diameter is a central portion 30 of a larger diameter than the end portion fitting in the bearing 27 and of smaller diameter than the end portion received in the face plate, which is adapted to receive a sleeve member 31 carrying a plurality of insulating rings or discs 32, adapted to mount a plurality of slip rings 33, therebetween, in insulated relation with respect to each other, and the shaft or cylindrical portion 30 thereof. The bearing 27 and the slip ring construction is suitably held within a dust tight casing 34, mounted 10 on the supporting plate 28, and having a pack joint around the flange extending from the plate 24 as indicated at 35. Within the casing 34 and mounted in the supporting plate or flange 28 are a plurality of rods 36, 15 arranged in concentric relation with respect to the shaft 26, and extending inwardly and overlying the slip ring 33 carried by the shaft. These rods are adapted to support suitable contact brushes 37, arranged in spaced relation on said rods 36 and insulated from each other, adapted for contact with respective rings 33, above described, in a manner as clearly illustrated in Figure 3. Suitable circuit wires, (not shown), connect 20 the brushes with a source of power for the heating element and the indicator, with the thermocouple, so that in the operation of the device, with a movable web passing over the roll, the thermocouples will operate the indicator according to the temperature difference at the points of sensitiveness thereof to 25 the paper, to indicate the moisture percentage in said web.

In the above described construction, it will be seen that the hot section is located in the central portion of the roll, and that heat will be applied to the web of material passing thereover in the central portion and the hot junction of the thermocouple will operate in conjunction with the central part of the web, while the cold junction of the thermocouple operates adjacent the edge of the web. When the circuit wire is connected to a pair of slip rings at the end of the rolls, shown in Figure 1, or interposed through the connections in the corresponding brushes in the circuit with a voltmeter of a desired type, the thermocouple circuit will operate the voltmeter to indicate the percentage of moisture in the web passing over the roll, when a predetermined amount of heat is supplied to the heating coil in the heating section 2, through the interposition of said coil in a circuit through the brush connection at the end of said roll 40 with the corresponding pair of rings connected to the heating element, as above described for supplying current thereto. It has been found, however, that under some conditions, the above described roll construction, while having substantially high prac-

tical advantages over other constructions heretofore used, will not successfully withstand the tensile and torsional stresses to which it is subjected in use, in connection with a paper machine for indicating the 70 moisture content of a web of paper.

As a result of the practical disadvantages of the above described roll, a reinforced construction has been provided therefor, of a slightly different character such as illustrated in Figure 4, which includes main shaft, sections 40, which are provided with reduced axial extensions at the opposite ends as at 75 41, for receiving the ring structure above described, and also fitting in the bearing 80 structure carried by the dryer frame of a paper machine or the like. The shaft sections 40 are connected by and support a tubular reinforcing shaft 42, between the reduced ends as clearly illustrated in Figures 5 and 85 6. The remaining structure of the roll is substantially similar to the one first described, including hot sections 43, intermediate sections 44, a cold section 45, and end sections 46. All of these sections are 90 united in roll forming relation by suitable junction members 47 mounted on the tubular reinforcing shaft 42, in a manner as clearly illustrated in Figure 5, and provided in the central portion with an annular flange 48, 95 against which the ends of the tubular casing sections 49 co-extensive with each of the sections abut. The casing sections 49 are secured to the junction members 47, in any suitable manner as above described, and in the hot section, a cylindrical heat resisting member 50 is positioned on the tubular shaft 42, and provided on the periphery thereof with a spiral groove for receiving the heating element 51 to provide the proper 105 amount of heat for this hot section. In the central portion of the hot section, the hot junction of the thermocouple is mounted in the usual manner, as indicated at 52, and provided with suitable wire connections in 110 a manner as above described, while suitable tubes 53 are provided for forming conduits extending axially of the roll, for said wires of the thermocouple and also of the heating element. In order to permit of ready access to the heating element and the hot section 43 of the improved roll construction, the casing section therefor is formed of a pair of sections of semi-cylindrical form, indicated 115 at 54 and 55 respectively, which are provided with overlapped interfitting tongue extensions as illustrated in Figure 7, to provide a smooth cylindrical outer surface on said section, co-extensive with the remaining surface of the roll. Suitable set screws or 120 the like 56 assemble the sections on the junction member and retain the same in proper assembled relation, during the normal operation of the roll, for determining 125 the moisture content of the web. The cold 130

section of the improved roll, indicated at 45 is also formed of a pair of semi-circular casing sections similar to the sections 54 and 55 and said cold section of the roll 5 mounts a pair of cold thermocouple junctions indicated at 57, to cooperate with the respective hot thermocouples 52 in the heating sections of the end portions of the roll, in a manner as clearly illustrated in Figure 10 4, the wiring connections between the same being designated in dotted lines. The end structure of the roll, at the ends of the casing sections or end sections 46 are reinforced by supporting rings 58, fitted on the ends 15 of the tubular reinforcing shaft 42, and are adapted to receive end plates 59 bolted thereto, in a desirable manner for finishing the end structure of the roll. In this reinforced construction, it will be seen that the web will 20 be heated at or adjacent the opposite sides thereof where the hot junction of the thermocouples are positioned, while the corresponding cold junctions of the thermocouple are positioned in the central portion of the 25 web, and the top pairs of hot and cold junctions connected together to the corresponding or desired slip rings, for connection in circuit with a suitable voltmeter indicated at 60 illustrated diagrammatically in Figure 30 4, while the heating elements are connected with a suitable source of power measured by a wattmeter 61 and controlled by a suitable variable resistance 62. It will be seen, from this construction, that a substantial 35 improvement has been made in the roll construction, whereby the same will withstand substantially great torsional strains in the operation of the roll, and at the same time will more accurately determine the moisture 40 content of the paper by the plurality of indicating devices connected with the corresponding heating elements and thermocouple circuits.

In Figure 8, the manner of connecting the 45 roll, for operation in connection with a paper machine is illustrated diagrammatically, wherein the larger circles as indicated at 63 represent the last two rolls of a dryer for a paper machine from which the paper passes 50 over an idler roll 64, and subsequently to the improved measuring roll, above described, as indicated at 65, wherein the moisture content of the paper is determined, through the operation of the thermocouples 55 and voltmeter, such as illustrated at 60, in Figure 4.

From the foregoing description, it should be readily appreciated that a substantially improved roll construction has been provided, wherein the same is constructed for mounting all of the means adapted to contact with and operate through suitable connections, the indicator from which the moisture percentage of the paper may be determined.

The means for obtaining the temperature difference includes the use of a milli-volt meter or potentiometer which is indicated in the drawings by the numeral 60 and is preferably calibrated to read directly in terms of percent moisture contained in the paper, and the principle involved in the calibration may be mathematically shown as follows:—

$$(T_2 - T_1)(W_w \times S_w + W_p \times S_p) = Q$$

where

T_2 = temperature of paper after heating.

T_1 = temperature of paper before heating.

W_w = weight of water contained in the paper plus the weight of dissolved substances.

S_w = specific heat of above.

W_p = weight of bone-dry paper passing over the instrument in unit time.

S_p = specific heat of above.

Q = quantity of heat supplied in unit time.

For a given rate of production on the paper machine, all of the above factors will be known except W_w , (assuming S_w equals 1). The quantity W can therefore be calculated from which the percentage moisture in the paper can be found thus:

$$\frac{W_w}{W_p + W_w} \times 100 = \text{per cent moisture.}$$

What is claimed is:

1. In combination, an indicator, an operating means therefor comprising a rotatable element adapted for contact and rotation with a movable web, heating means mounted in said element for heating a portion of the web, heat responsive means mounted in said element for contact with the web at the heated portion and at an unheated portion and, responsive to the difference in temperature of the web at the points of contact, and means operatively connecting the heat responsive means with the indicator for operating said indicator to register the percentage of moisture in the web.

2. In combination, an indicator, an operating means therefor comprising a rotatable element adapted for contact and rotation with a movable web, heating means carried by the element for heating a portion of the web, heat responsive means mounted in spaced relation in said element for contact at spaced points with the heated and unheated portions of the web and responsive to the difference in the temperature of the web at the heated and unheated portion thereof, and means connecting said spaced heat responsive means to said indicator for operating the indicator to register the moisture percentage of the web.

3. In combination, an indicator, an operating means therefor comprising a rotatable element adapted for contact and rotation with a movable web, said element having hot

sections and cold sections, heating means in the hot sections, heat responsive means mounted in both sections responsive to the difference in temperature of the web contacting with the respective sections, and means connecting said heat responsive means with said indicator for operating the indicator to register the moisture percentage of the web.

4. The combination, of an indicator, an operating means therefor comprising a rotatable element adapted for contact and rotation with a movable web, a hot thermo-couple junction and a cold thermo-couple junction mounted at spaced points in said element and responsive to the difference in temperature of the web between said points, means for heating the web at the portions effecting the hot junctions, and connections between said junctions and the indicator for operating the indicator to register the moisture percentage of the web.

5. In combination, an indicator, an operating means therefor comprising a rotatable element adapted for contact and rotation with a movable web, heating means in said element for heating the web at a predetermined portion thereof, heat responsive means mounted in said element responsive to the difference in temperature between the web at the heating means and the web at spaced intervals therefrom, and connections between the heat responsive means and the indicator for operating the indicator to register the percentage of moisture in the web.

35. 6. An operating device for an indicator for registering the percentage of moisture in a web comprising a roll mounted for rotation in contact with a movable web, heating means mounted in said roll for heating a portion of the web, heat responsive means mounted at spaced points, one of said points being adjacent said heating means in said roll responsive to the difference in temperature of the web between said spaced points, and connections between the heat responsive means in the roll and the indicator.

7. An operating device for an indicator for registering the percentage of moisture in a web comprising a roll having a plurality of sections assembled in axial alignment and mounted for rotation in contact with a movable web, heat responsive means mounted in predetermined sections, heating means in a predetermined section one of said heat responsive means being in the section with the heating means, and responsive to the difference in temperature of the web, between said predetermined sections and connections between said heat responsive means and the indicator.

60. 8. An operating device for an indicator for registering the percentage of moisture

in a web comprising a roll having a plurality of casing sections, means for assembling said sections in roll forming relation, thermocouples mounted in pre-determined sections responsive to the difference in temperature of a web passing over said roll between said thermocouples, means mounted in one of said predetermined sections for heating the section, said roll having shaft extensions on the opposite ends thereof adapted to be rotatably mounted in suitable bearings, and connections between said thermocouples and slip rings carried by said shaft extensions, whereby the thermocouples may be interposed in a circuit with the indicator.

9. An operating device for an indicator for registering the percentage of moisture in a web comprising a roll formed of a plurality of axially arranged sections assembled in roll forming relation, heat responsive means mounted in predetermined sections of said roll responsive to difference in temperature of the web at predetermined spaced points, heating elements mounted in predetermined sections of said roll for heating portions of the web, portions of the heat responsive means being in the same section with the heating element, and connections between said heating elements, the heat responsive means, and independent means beyond the ends of the roll rotatable therewith, whereby the heating element and heat responsive means may be interposed in circuits beyond said roll.

10. An operating device for an indicator for registering the percentage of moisture in a web comprising a roll formed of a plurality of casing sections, junction means securing said sections in assembled, axial aligned relation to form the roll, supporting means for said roll projecting beyond the ends thereof adapted to be received in bearings for rotatably mounting the roll for contact with the web, heating elements adapted to be positioned within predetermined sections of said roll, supporting means for said heating element within said section, thermocouples mounted in predetermined sections including the sections containing said heating elements of the roll responsive to difference in temperature of the web passing over the roll at predetermined spaced points, slip rings mounted on said roll supporting means beyond said roll, connections between the heating elements, the thermocouples, and predetermined slip rings, whereby said heating element and thermocouples may be connected in circuits beyond said roll.

In testimony whereof I affix my signature.
ARTHUR R. HARVEY.
